Specification for Design.

Patented Nov. 2, 1920.

Application filed March 19, 1920. Serial No. 367,109. Term of patent 3½ years.

To all whom it may concern:

Be it known that I, ARDIE WILLIAMS, a citizen of the United States, residing at Los Angeles, county of Los Angeles, and State of California, have invented a new, original, and ornamental Design for Tonneau-Windshields, of which the following is a specification, reference being had to the

accompanying drawing, forming a part thereof.

The figure is a front elevation of a tonneau windshield showing my new design.

I claim:

The ornamental design for a tonneau windshield, as shown.

ARDIE WILLIAMS.
